UNITED STATES PATENT OFFICE

ARTHUR A. ARNOLD, OF NEW HAVEN, CONNECTICUT, ASSIGNOR TO THE A. C. GILBERT COMPANY, OF NEW HAVEN, CONNECTICUT, A CORPORATION OF MARYLAND

DESIGN FOR A HEATING PAD

Application filed December 1, 1931. Serial No. 41,932. Term of patent 14 years.

To all whom it may concern:

Be it known that I, ARTHUR A. ARNOLD, a citizen of the United States, residing in New Haven, in the county of New Haven and State of Connecticut, have invented a new, original, and ornamental Design for a Heating Pad, of which the following is a specification, reference being had to the accompanying drawing, in which—

Fig. 1 is a face view of a heating pad; and Fig. 2 is a section on line 2—2 of Fig. 1 of the envelope of the pad, the interior parts being omitted.

I claim:

The ornamental design for a heating pad substantially as shown and described.

ARTHUR A. ARNOLD.
